Primary Examiner — David G Muller*Assistant Examiner* — Nathan M Johnston(74) *Attorney, Agent, or Firm* — Park & Associates IP Law, P.C.(57) **CLAIM**

The ornamental design for a surfboard cradle, as shown and described.

DESCRIPTION

FIG. 1 is a perspective view of the surfboard cradle in accordance with the new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a reference view illustrating a usage of the surfboard cradle with a main surfboard.

The broken lines are shown for environmental purposes only and form no part of the claimed design.
